INSTALLATION FOR PAVEMENT JOINTS

Edward McCrady, Jr., Pittsburgh, Pa.

Application August 29, 1934, Serial No. 741,922

8 Claims. (Cl. 94—18)

This invention pertains to highway or pavement joints, and more particularly, to structure for installing joints which divide a pavement into slabs.

5 Rigid pavements of concrete, cement, brick, etc., are materially affected by changes in temperature and moisture content and provision is generally made to take care of dimensional changes and reduce the internal stresses and 10 strains caused by expansion and contraction.

As a result, it has been customary to divide the concrete or other paving material into smaller portions or slabs by employing longitudinal and transverse joints. In accordance with the present practice, particularly when installing the 15 transverse joints, it has been customary to provide preformed or molded sections of a suitable fibrous or felt material impregnated with some bituminous material. These sections are nor-

20 mally held in place by means of a special bulkhead or wooden board known as a placing bar, until the concrete has been deposited on both sides. The bulkhead is then carefully pulled and the concrete tamped under it to prevent the filler 25 sections from being displaced. After this, the concrete is finished.

The difficulty encountered with many such devices is the tendency to pull the filler out along with them. Special devices are needed to hold 30 the filler down.

An object of my invention is to provide new and improved means for installing dimensionally extending joints.

Another object is to provide new and improved 35 structure for installing such joints.

A further object is to provide what may be termed a permanently located bulkhead.

A still further object is to provide a more effective and/or more efficient joint installation for 40 pavements.

These and many other objects of my invention will appear to those skilled in the art from the following description taken in view of the appended claims and the drawing, in which:

45 Figure 1 is a longitudinal plan view of a structure employed in carrying out an embodiment of my invention;

Fig. 2 is a longitudinal elevational section showing the embodiment of my invention of Fig. 1 in 50 a mounted relationship with respect to a pavement construction;

Fig. 2a is a plan section of a detail, taken along the line IIa—IIa of Fig. 2;

Fig. 2b is a vertical elevational view of a modi- 55 fication of the bracket shown in Fig. 2.

Fig. 3 is a reduced plan of a section of a roadway showing diagrammatically a transverse joint installation employing joint structure such as shown in the embodiment of Fig. 1;

Fig. 4 is a reduced longitudinal elevational section showing another structural embodiment of 5 my invention in a mounted relationship with respect to a pavement construction, and

Fig. 5 is a vertical section of a detail taken 10 along the line V—V of Fig. 4.

From one aspect, my invention deals broadly with an improved support structure for joint installations employed in connection with pavement constructions.

In another aspect, my invention deals with an 15 improved structure for installing transverse joints in pavement constructions.

My invention involves means for interposing an 20 expansion joint in road paving material, such as concrete and for the sake of simplifying the further description of the invention, I will briefly 25 describe the means utilized in forming or installing such an expansion joint.

In the construction of a road, the location of 30 expansion joints is usually predetermined and 25 designated prior to the laying of the paving material and by my invention I provide a structure which facilitates the installation of expansion joints at the designated points without materially interfering with or substantially reducing the rate 35 of progress of pouring the concrete or road metal. My improved structure may not only be quickly assembled, but may be accurately and rigidly positioned at the designated point for the expansion 40 joint and not only serves to support the material constituting the expansion joint, but also serve to position and hold in place the joint dowel bars which are employed for the purpose of preventing relative vertical motion between the adjacent portions of the paving slabs on opposite sides of the 45 expansion joint.

In accomplishing this, I provide a metal plate 50 so formed that it is capable of being quickly and rigidly installed at the point of the expansion 45 joint and which is of such character that it may be retained in position after the pouring operation is completed. This plate is preferably of such length that it extends along or across the paving material to be subsequently poured and is 55 of such form that it is readily held in a vertical position by means of stakes driven into the sub-grade of the road. As herein illustrated, the plate is of a width equal to the thickness of the concrete slab to be produced and its upper edge 55

is so formed as to conform to the surface contour of the slab.

The plate is also so formed as to provide stake receiving apertures therein which are preferably 5 equally spaced longitudinally of the plate and are so located that they do not interfere with or in any manner impede the operation of securing the expansible material to one side of the plate. In addition, the plate is provided with dowel bar 10 positioning means which are so formed and located that they not only do not interfere with the operation of pouring the road metal, but also are of such form and construction that they hold the dowel bars rigidly in the desired and designated positions.

From the foregoing it will be apparent that the procedure here contemplated not only involves the rapid and accurate positioning of the expansible material at the point of the expansion joint, but 20 it also involves the rapid and accurate positioning of the dowel bars so as to insure that both the expansible material and the dowel bars are properly located and positioned in the paving material when that material is subsequently 25 poured. The plate and the dowel-positioning means secured to it remain in position after the road pouring operation is completed.

The dowel bar positioning means is preferably 30 so proportioned, constructed, and/or located that it will "give" during movement between the slabs of the pavement which lie adjacent the joint.

It will appear that the joint structure is designed and installed in such a manner as to support and maintain itself in alignment during the 35 pouring and setting of the concrete road metal. As seen in the diagrammatic view of Fig. 3, the joint is laid out or installed, and then, concrete road metal from a mixer 40 is discharged from a chute 41 against both sides of the line of the 40 proposed joint until the desired depth of road metal has been obtained. In this figure the work is advancing from the right to the left.

I have been able to eliminate the disadvantages 45 of the commonly employed bulkhead joint structure by providing a structure that may be permanently retained in position. This structure is so positioned and located that it adds to the strength of the adjoining slabs as well as to the strength of the joint itself. Then, too, the procedure employed is materially simplified and there is very little, if any opportunity to "spoil" 50 the concrete work as frequently occurs when the bulkhead is pulled out.

Referring to the drawing, I will designate some- 55 what similar parts of the illustrated embodiments of my invention by the same numerals, but will differentiate between embodiments by prime suffixes.

As shown in Fig. 2, I provide a fibrous strip 60 10 which in height corresponds to the depth of pavement slabs 8 and 9, but if desirable, its height can be made slightly greater and the filler cut off after the pavement has been finished. In this connection, although each joint plate 11 also 65 has a height such that its top edge aligns exactly with the concrete or cement slabs, it may be desirable in certain installations to shorten the height of the plate and to position it slightly below the surface. This permits the edges of the slabs to chip, but protects the plate from traffic wear. Bituminous material can be employed as a filler to protect the edges of the slabs adjoining such a plate, in such a case.

In the illustrated embodiment of my invention 75 shown in Figs. 1 and 2, I have provided the joint

plate structure 11 with a somewhat centrally-located, angle-like or V-shaped projection 12 and with an outwardly extending base portion 15; the projection 12 is and the portion 15 may be suitably punched out, in order to receive a vertically-extending positioning pin 30 which is preferably driven into the sub-grade 1. The pin 30, as shown particularly in Fig. 2, extends downwardly in abutment with the edges of a vertically-extending hole in the projection 12, and may extend through a punched-out portion in the base projection 15 to align and rigidly secure the plate 11 in position. For a joint installation having a considerable length, it is preferable to locate a plurality of positioning pins 30 at a number of 15 spaced points along the length of the plate 11. The pins need not necessarily extend through the brackets 14, but may be driven down in abutment with side edges thereof or at a spaced position therefrom, see the pin 30a, represented by dotted 20 lines in Fig. 1.

As seen, the joint plate 11 is also provided with associated means for supporting one or more longitudinally and horizontally extending dowel bars 20. This means includes a horizontal 25 punched-out portion of the V-shaped projection 12 and a horizontal punched-out portion 16 of an upwardly projecting bracket 14. In like manner, the fibrous strip 10 is also punched out to permit the dowel bars 20 to pass therethrough. 30

The dowel bar 20 is positioned to extend across the joint substantially centrally of the depth of the adjacent or opposite slabs 8 and 9, and longitudinally into each slab. The dowel bar 20 has what may be termed a spaced-three-point suspension or support. In order to prevent a bond 35 between the dowel bars 20 and the immediately associated concrete or cement slab, the bar is preferably painted and then greased, or merely greased. This permits the slabs to expand and 40 contract without breaking the dowels or chipping the concrete.

In addition, I provide end spacing for permitting the bar to slide in and out with respect to 45 at least one of the slabs which, in this case, is the slab 9. This calls for the provision of an open space in the slab the size of the bar 20 which is long enough to permit movement of one or both ends of the bar. Thus, I provide a cap or sleeve 21 in the form of a metal or fiber tube, which in 50 this case is shown as the latter and is mounted over an end of the dowel bar 20, and has a space between its end and the end of the bar to permit movement of the former.

The joint plate may be constructed in any other 55 suitable form or pattern and any suitable material may be employed such as a wire mesh, or a solid or patterned piece of metal.

If the dowel bar and the joint plate do not have the exact positioning desired, for example, the 60 dowel bar may incline from one slab to the other, then unequal stresses and strains may be set up, the joint will not function as it should, and the bar may soon break or the concrete chip out on top of it. Thus, it is highly important that the 65 dowel bar and the joint plate as well as the fiber strip be positively aligned and held in the desired position during the pouring of the pavement material and during its setting process.

I have found that the problem may be solved 70 by providing a bracket structure such as 14 which, in itself, forms a part of the joint plate. It may be secured thereto adjacent its bottom center portion 15 and extend upwardly therefrom in order to receive the longitudinally and horizontally ex- 75

tending dowel bar. In this way, the joint plate, the bracket and the dowel bar form a closed figure whose parts are held in alignment by their relationship with respect to each other, and additionally, by the stake-like element or pin 30 which may cooperate with the closed structure.

In the embodiment of my invention shown in Figs. 1 and 2, the bracket has what may be termed a U or V-shape, and in the embodiments 10 of Figs. 4 and 5 has what may be termed an M-shape.

The M-shaped structure 14' of Fig. 4, like the V-shaped structure 14 of Fig. 2, has a central portion 15' secured to the bottom of the associated 15 joint plate 11' by some suitable means such as a weld 13', but unlike the previously discussed embodiment, is provided with a pair of oppositely and downwardly extending legs or stake-like pins 16', which may be and preferably are, driven into 20 the sub-grade 1. As seen the portion 15 of the embodiment of Figs. 1 and 2 presents a flat support surface, while the portion 15' of the embodiments of Figs. 4 and 5 presents an angular or inclined support surface. The bracket structure 14' is preferably of a channel shape, see Fig. 5, in order to more readily support the dowel bar 20'. A sleeve or ring 17' extends upwardly from the bracket adjacent each of its body portions 14' and forms a positioning loop through which a 25 dowel bar may extend. As seen in Fig. 5, the dowel bar 20' may be notched adjacent one side 21' in order that the ring 17' may be pulled tightly thereagainst to prevent a turn of such dowel bar with respect to the bracket 14'.

Further, in accordance with my invention, I contemplate the employment of support bracket structure which will allow for relative movement between the slabs 8 and 9, and since the dowel bars 20 prevent much vertical movement, 40 which will particularly allow for horizontal expansion between the slabs.

Since the bracket structure need not be retained in a unitary form after the concrete has set, its portion 15 lying adjacent the joint may 45 be so proportioned as to break or shear off during relative movement between the slabs. If portions 15 have a slender outline (see their strap-like thickness in Fig. 2), no further provision need be made. However, as seen in Fig. 2a, the portion 50 15 may be provided with transverse perforations, or a slot or groove 15a, in order to facilitate braking.

In the modified form of bracket 14a shown in Fig. 2b, the base portion 15b has a somewhat 55 U-shaped outline and is adapted to clamp over bottom portions of the filler strip 10 and the joint plate 11. This form of bracket need not be secured to the plate 11, but in any event, if it is secured to the latter, it will preferably be welded 60 to it adjacent its base edge. Since the portion 15b fits over the bottom portions of the filler strip and the joint plate with a spring-like clamping action, it follows that it will also permit relative expansion between the slabs 8 and 9 with a 65 spring-like action and no provision need be made for deliberately breaking such a type of bracket into two or more parts.

In the embodiment of my invention shown in Fig. 4, the bottom portion 15' of the bracket 70 will more readily shear off along the base line of its relatively sharp or acute angle.

As previously pointed out, in Fig. 3, I diagrammatically show a cement or concrete mixer 40 having a feed or discharge chute 41. This view 75 has been added in order to clearly disclose the

procedure employed in constructing a concrete pavement or highway having a transverse joint embodying the principles of my invention. This figure diagrammatically points out the relationship or spacing between a plurality of dowel bars such as shown in the embodiments of Figs. 2 and 4, each of which has been represented generally by the letter "a". After a plurality of such bars have been aligned transversely and longitudinally as shown, then the concrete may be 10 poured or placed around them to finish the two adjacent slabs 8 and 9.

In this connection, by way of example, the pavement may be provided with a $\frac{3}{8}$ or $\frac{1}{2}$ " joint spacing; and, each dowel bar "a" may have approximately a 27 inch spacing with respect to adjacent bars.

While various modifications and changes may be made in the structure herein disclosed, it will be apparent to those skilled in the art that such 20 changes may be made without departing either from the spirit or the scope of the invention. It is desired, therefore, that only such limitations shall be placed on the invention as are imposed by the prior art and the appended claims. 25

What I claim as new and desire to secure by Letters Patent is:

1. In a structure for installing a joint in a pavement, the combination of a treated fibrous strip, means adapted to abut against said strip for 30 holding it in position during a pouring of pavement metal, said means having a length substantially corresponding to the length of the proposed joint and bracket and dowel means for permanently securing said holding means with re- 35 lation to the pavement.

2. In a structure for installing a joint in a pavement, the combination of at least one plate adapted to extend upwardly the depth of the proposed pavement, support means secured to 40 the bottom of said plate and extending upwardly therefrom, said support means being positioned in such a manner that it will be embedded when pavement metal is poured to form the joint, a hole punched in said plate and at least one hole 45 punched in said support means in alignment with the hole in said plate, and a longitudinally extending dowel bar mounted in said punched holes.

3. In a positioning plate for a pavement joint which is adapted to be permanently mounted as 50 a part of the pavement structure, the combination of a body portion having a vertical dimension corresponding substantially to the proposed depth of a pavement slab, a V-shaped bracket portion centrally secured to a base of said body portion and extending outwardly therefrom, said body portion and said bracket portion having portions for supporting a dowel bar.

4. In a positioning plate for a pavement joint which is adapted to be permanently mounted as 60 a part of a pavement structure, the combination of a body portion having a vertical dimension corresponding substantially to the proposed depth of a pavement slab, an M-shaped bracket portion centrally secured to a base of said body portion and extending outwardly therefrom, said body portion and said bracket portion having portions for supporting a horizontally-extending dowel bar, the legs of said M-shaped bracket 65 being pointed for driving into a sub-grade of a roadway upon which the pavement is to be constructed.

5. In a structure for installing a joint in a pavement which includes, a dowel bar and means extending across the proposed joint and support- 75

ing opposite portions of said dowel bar during a pouring of pavement metal, said means having portions providing a spaced-three-point support for said dowel bar, said means having a spring-like portion adapted to be positioned adjacent the joint, so that the pavement may move about the joint after the metal has set.

6. In a structure for installing a joint in a pavement, a combination of a treated fibrous strip, means adapted to abut against said strip for holding it in position during a pouring of pavement metal, means for permanently securing said holding means with relation to the pavement, means cooperating with said strip and said holding means and being supported by the latter, said last-mentioned means having oppositely extending portions for supporting a dowel bar during a pouring of pavement metal, said last-mentioned means having a yieldable portion for permitting relative movement between slabs of the pavement adjacent the joint after the metal has set.

7. In a positioning structure for a pavement joint, the combination of a plate-like body portion having a depth corresponding substantially

to the depth of a proposed pavement slab, a bracket portion secured to the base of said body portion and having a pair of arms extending upwardly therefrom, a dowel bar, means on each of said arms for receiving and aligning said dowel bar, said bracket portion having downwardly extending portions for driving into a subgrade.

8. In a pavement construction having a pair of oppositely-positioned slabs connected by a suitable joint, the combination of a joint plate extending along the joint and between said slabs, said joint plate having a vertical dimension corresponding substantially to the vertical dimension of said slabs, a bracket means having a central portion secured to the bottom of said joint plate, said bracket means extending upwardly from said joint plate into each of the slabs, a horizontally-positioned dowel bar mounted upon said bracket means and extending through said joint plate for connecting up the slabs, a vertically-positioned dowel bar extending downwardly through said joint plate into a subgrade of the pavement.

EDWARD McCRADY, JR. 25
